UNITED STATES PATENT OFFICE.

GOTTLÖB F. HONOLD, OF SHEBOYGAN, WISCONSIN, ASSIGNOR TO HONOLD MANUFACTURING COMPANY, OF SHEBOYGAN, WISCONSIN, A CORPORATION OF WISCONSIN.

BATHTUB LEG.

Application filed November 27, 1922. Serial No. 603,598.

To all whom it may concern:

Be it known that I, GOTTLÖB F. HONOLD, a citizen of the United States, and resident of Sheboygan, in the county of Sheboygan and State of Wisconsin, have invented new and useful Improvements in Bathtub Legs, of which the following is a description, reference being had to the accompanying drawings, which are a part of this specification.

10 This invention relates to improvements in bath tub legs, and particularly to legs of this type which are constructed separately and are adapted to be then secured in position.

Heretofore legs used for supporting bath 15 tubs and the like have been formed of cast metal, having a dove-tail connection with the bottom portion of the tub. Legs constructed in this manner are expensive and are furthermore liable to become broken during 20 shipping. Furthermore, because of the excessive weight of cast metal legs, freight charges on the same are expensive.

It is therefore the primary object of this 25 invention to provide a bath tub leg which will not be subject to the above disadvantages, the leg being made of one piece of sheet metal, suitably shaped for accomplishing the connection with the tub or the like. In this manner the weight of the leg is materially reduced without in any wise affecting 30 the rigidity and durability of the same. The leg is constructed of sheet metal bent to a substantially U-shape in cross section, and the upper end thereof is suitably formed for 35 accomplishing the connection with the tub.

The details of construction of this invention will be made more apparent as the description proceeds, especially when considered in connection with the accompanying 40 drawings wherein;

Figure 1 is a front view of a leg constructed in accordance with this invention, a portion of a bath tub being shown in section;

Fig. 2 is a side elevation of the leg;

45 Fig. 3 is a top plan view;

Fig. 4 is a transverse sectional view taken on the plane indicated by the line 4—4 of Fig. 1, looking in the direction of the arrows; and,

50 Fig. 5 is a similar view of a modified form of construction.

Referring now more particularly to Figs. 1 to 4, the first form of the invention will be described. In these figures the reference 55 character 10 indicates a leg which is formed

of an integral sheet of metal, substantially U-shape in cross section. The contour of the leg may be such as to conform to the designs usually employed, the leg in all outward respects resembling the cast metal legs formerly employed.

The upper edge of the leg is bent to form an inwardly extending flange 11 which is adapted to engage dove-tail flange portions 12, formed on the bath tub or the like, 13. 60 The flange 11 is notched as at 14 to co-operate with lugs 15 formed on the dove-tail flanges 12, so that when the leg 10 is placed in position, the notches 14 will snap into engagement with the lugs 15, thus preventing accidental disengagement of the leg.

In Fig. 5 the notches 14 are replaced by projections 16, formed on the flange 11 at the ends thereof, these projections snapping over the inner ends of the dove-tail flanges 12 of 70 the tub, after the leg has been placed in position.

The manner of securing the legs will be immediately obvious inasmuch as it is only necessary to cause the flange 11 of a leg to be 80 inserted between the dove-tail flanges 12 and the bottom of the tub 13. In either construction, means are provided for preventing any accidental disengagement of the leg from the tub, after the same has been connected 85 thereto.

In manufacturing legs in accordance with this invention it has been found that all of the advantages inherent in the cast metal legs heretofore manufactured, are present in this 90 present construction, without, however, the heretofore known disadvantages. The legs constructed in accordance with this invention may be more cheaply and quickly manufactured, are not likely to become broken, and 95 are considerably lighter in weight so that freight charges on the same are considerably less. The connecting flanges at the top of the legs, which heretofore have been made by casting, are now made by bending the 100 edge of the leg, as will be immediately apparent.

The invention therefore consists essentially in the particular construction described, although it will be obvious that certain modifications may be made without departing from the spirit and scope of the invention, and to this end reservation is made to make such changes as may come within the purview of the accompanying claims.

Having thus described the invention what is claimed is:

1. The combination with a bath tub having dove-tail flanges of a sheet metal leg, a flange formed on the end of said leg by bending the edge thereof, said flange engaging said dove-tail flanges and inter-engaging means on said flanges for locking said leg in place.
- 10 2. The combination with a bath tub having dove-tail flanges for engaging a detachable leg, of a leg formed of sheet metal and U-shaped in cross-section, the end of said leg being bent to form a flange, said flange engaging said dove-tail flanges for locking said leg to said bath tub and co-operative means on said flanges for locking said leg in place.
- 20 3. A leg for bath tubs provided with flanges, said leg being formed of sheet metal and U-shaped in cross-section, one end of said leg being bent at right angles to form a flange, said flange engaging the flanges on said bath tub for securing said leg thereto, and means on said leg flange co-operating with said bath tub flange for locking said leg in place.
- 25 4. The combination with a bath tub hav-

ing dove-tail flanges for engaging a detachable leg, of a leg formed of sheet metal and U-shaped in cross-section, the end of said leg being bent to form a flange, said flange engaging said dove-tail flanges for securing said leg to said bath tub and means on said flanges for preventing a disengagement of said flanges.

30 5. A leg for bath tubs provided with flanges, said leg being formed of sheet metal and U-shaped in cross-section, one end of said leg being bent at right angles to form a flange, said flange engaging the flanges on said bath tub for securing said leg thereto and means on the flange formed on said leg for preventing accidental disengagement of said flanges.

40 6. The combination with a bath tub having dove-tail flanges of a sheet metal leg, a flange formed on the end of said leg by bending the edge thereof, said flange engaging said dove-tail flanges and means on said leg flange and engaging recesses on said dove-tail flanges for preventing accidental displacement of said leg.

45 In testimony whereof, I affix my signature.

GOTTLOB F. HONOLD.
